CLAIM

The ornamental design for a perfume bottle, as shown and described.

DESCRIPTION

FIG. 1 is front view of a perfume bottle according to the present invention.

FIG. 2 is a top view thereof.

FIG. 3 is a right side view thereof.

FIG. 4 is a left side view thereof.

FIG. 5 is a bottom view thereof.

FIG. 6 is rear view thereof; and,

FIG. 7 is a perspective front, bottom and left side view thereof.

The broken line showing of a bottom of the bottle in FIG. 5 is included for the purpose of illustration only and forms no part of the claimed design.
